CONCRETE BREAKING MACHINE

Walter V. Cornett, Los Angeles, Calif.

Application June 17, 1948, Serial No. 33,603

6 Claims. (Cl. 262—13)

1

The present invention pertains to improvements in concrete breaking machines.

An object of the invention is to provide a machine of the above nature including a supporting frame and a hammer mechanism providing improved mounting means for the hammer mechanism and for adjusting the vertical position of the latter.

Other objects and advantages of the invention will appear in the course of the following description in connection with the accompanying drawings, in which

Figure 1 is a rear elevation of a preferred form of the invention;

Figure 2 is a side elevation of the same;

Figure 3 is a downwardly directed sectional view in the plane 3—3, Figure 2;

Figure 4 is a detail front elevation of the hammer operating structure;

Figure 5 is a vertical sectional view of the same;

Figure 6 is a fragmental detail view of the vertical locating latch structure;

Figure 7 is a vertical sectional view of the same on the lines 7—7, Figure 6;

Figure 8 is a side elevation of the device showing an alternative form of elevating and cushioning means; and

Figure 9 is a diagram illustrating the operation of the machine in a circular path about one wheel as a pivot.

Referring to Figures 1, 2 and 3, the numeral 10 denotes a frame of generally triangular shape, preferably of welded steel construction. A front wheel 11 is vertically swivelled by a pivot 12 in a support 13 secured to the front corner or apex of the frame 10. A drag bar 14 is attached to the upper end of the pivot 12 for coupling to a truck or hauling means. The bar 14 is horizontally hinged at 15 so that it may be swung upward to vertical position when desired, and a laterally extending handle 16 is secured to the bar to permit the latter to be operated as a steering post. A latch 17, Figures 2 and 3, is provided to hold the bar 14 in vertical position. The wheel 11 carries a pneumatic tire 18.

Two parallel rear wheels 19 and 20 are rotatably mounted on an axle 21 secured to the rear of the frame 10 by means of legs 21a and are also provided with pneumatic tires 22 and 23 respectively. The wheel 19 has attached thereto a sprocket 24 connected by a chain 25 to the driving sprocket 26 of a reversible compressed air motor 27 secured to the underside of the frame 10. Two transverse shafts 28 and 29, rockably secured to the frame

2

10, have attached to their outer ends curved brake shoes 30 and 31 adapted to engage the upper peripheries of the tires 22 and 23 respectively. Arms 32 and 33 on the rocker shafts 28 and 29 are connected by toggle links 34 and 35 with pivots 36 and 37 in the rearwardly extending arms 38 and 39 of bell-cranks 40 and 41, the vertically directed arms 42 and 43 of the bell-cranks 40 and 41 comprising handles for applying the brakes.

10 When the handles 42 and 43 are thrown rearwardly to apply the brakes, the pivots 36 and 37 may be thrown below center against the resilient resistance of the tires 22 and 23, the resilient pressure of the tires thereafter holding 15 the mechanism in toggle locked position with the brakes in engagement. It will be noted that the two brake mechanisms are independent of each other, allowing either brake to be operated without the other as desired. Light retracting springs 44, attached to the toggle pivots 36 and 37, serve to normally hold the brakes in disengaged position.

A pair of vertical channel members 45 and 46, Figures 1 and 2, secured to the frame 10, form 20 guide-ways for a cross-head member 47. A second pair of channel members 48 and 49 similarly form parallel guide-ways for a second cross-head member 50, Figure 1. A compressed-air cylinder 51, shown in detail in Figures 4 and 5, has a lower head 52 provided with opposite lateral extensions 53 and 54 journaled or trunnioned in the members 47 and 50 respectively.

Vertical supporting and positioning rods 55 and 56, secured to the upper sides of cross-heads 47 and 50, are slidably mounted in flanged guide members 57 and 58 disposed on synthetic rubber cushions 57a supported on plates 59 and 60 comprising the upper bracing members of the channel cross-head guides as shown in detail in Figure 7. The flanged guides 57 and 58 are vertically movable on bolts 61, and are normally held down against the cushions 57a by compression springs 62.

45 The front sides of the rods 55 and 56 are provided with series of parallel slots or notches 63 adapted to receive latches 64 and 65, pivotally secured to lateral extensions of the flanged guide members 57 and 58. The latches 64 and 65 normally rest in any chosen pair of notches 63, thus supporting the cross-heads and air cylinder at the desired height. Knuckle links 66 connect the latches 64 and 65 to lever arms 67 and 68 on a transverse shaft 69. A downwardly directed handle 70, Figures 1 and 2, when moved for-

wardly, rocks the shaft 69 and withdraws the latches 64 and 65 from the notches 63 when it is desired to change the vertical location of the air cylinder as hereinafter set forth.

It will be noted that the guide members 57 and 58 are slotted to receive the latches 64, and that when the latter rest in the rod notches 63 they lock the rods against motion either upward or downward in the guide members.

The vertical channel guides 45, 46, 48 and 49 are braced on the frame 10 by forward and rear members 71 and 72.

Referring to Figure 5, the numeral 73 denotes a pneumatic piston fitting in the cylinder 51 and secured on the upper end of a piston rod 74, slideable through the lower head 52 via a gland 75. The lower end of the rod 74 carries a massive hammer 76 adapted to receive and hold a breaker or cutting tool 77 of any desired form dependent on the type of work. A vertical guide rod 78 is fastened in a rearward extension 79 of the lower cylinder head 52, and a lug 80 on the hammer 76, slideable on the guide rod 78, prevents the hammer from turning during operation.

A laminated semi-elliptic spring 81 is secured to an angle plate 82 bolted to the end of the axle extension 53. The spring 81 bears against a vertical angle-guide 83 welded or otherwise secured to the channel-member 45. The spring 81 normally holds the hammer and operating assembly in vertical position, but is yieldable to allow limited forward or rearward swing of the assembly in the cross-heads 47 and 53 when such shifting facilitates certain types of work.

A four-way valve 84 (Figs. 1 and 2) provided with an exhaust duct 85 and an inlet fitting 86 for attachment of a flexible air-supply hose, is connected via flexible hoses 87 and 88 to the lower and upper ends of the cylinder 51. A handle 89 on the valve 84 is manually operable to admit compressed air above or below the piston 13 for controlling the up and down action of the hammer and tool.

A second valve 90, having an air supply connection 91 and connecting tubes 92 and 93 to the reversible air-motor 27, is also manually operable by a handle 94 to control the air motor. A foot-pedal control 94a, Figure 3, may also be provided for the valve 90.

The numeral 95, Figures 2 and 3, designates a small oil reservoir from which oil may be fed through a tube 96 to the cylinder 51.

A suitable seat 97 is secured to the frame 10 in position to place the previously described control levers and steering means within convenient reach of the operator.

In operation, the machine is connected to a suitable source of compressed air and maneuvered into position to line up the hammer 76 and tool 77 above the point at which the work is to be started. The height setting of the cylinder 51 is adjusted to bring the effective stroke of the hammer to the desired depth of cutting position. The vertical adjustment of the cylinder is accomplished in the following manner:

If it is desired to lower the cylinder 51, the control valve 85 is operated to allow the hammer 76 to sink until the tool 77 rests against the ground or other supporting surface such as concrete. The lever 70 is operated to withdraw the latches 64 and 65 from the notches 63 in the supporting rods 55 and 56. Air is then bled into the lower end of the cylinder and released from the upper end, permitting the entire cylinder assembly to move downward until the desired po-

sition is reached, whereupon the latches 64 and 65 are returned into engagement with the corresponding pair of notches 63 to lock the assembly in place. Similarly, when it is desired to raise the cylinder 51, the hammer or tool is placed against the ground or concrete surface, the latches 64 and 65 are released, and compressed air is admitted to the cylinder above the piston 13. As the latter is held stationary by the supporting surface, the air pressure moves the cylinder assembly upward until the required position is reached, the latches then being re-engaged with notches 63 to lock the assembly as before.

From the foregoing it will be seen that the preferred embodiment of the invention as described provides power elevation and adjustment of the assembly, entirely by action of the operating piston and cylinder themselves, promoting extreme simplicity and economy by elimination of any auxiliary elevating devices.

The long range of adjustment of the cylinder height permits the hammer 76 and tool 77 to be worked at depths well below the level of the supporting surface; for example, in deep cuts or trenches.

While the device has been described as directed principally to the breaking of concrete and the like, it is obviously adapted to performing various other related functions such as tamping back-fill in trenches, etc.

In breaking concrete, cutting, etc., the operator controls the strokes of the hammer 76 by means of the four-way valve, moving the device by means of the air-motor 27 and steering by the front wheel 14 to follow the line of work. A principal feature of the machine is the substantially uniform distribution of the weight on the three wheels and the location of the line of impact within the frame and closely adjacent the center of the triangle formed by the points of contact of the three tires with the ground. This balanced construction causes an even cushioning effect to be provided by the three tires, steadyng the machine against rocking or surging, and preventing any tendency to crawl or "walk" out of proper position.

Supplementing the cushioning effect of the pneumatic tires, further resilient shock absorption is provided by upward and downward movement of the plates 57 and 58 between the springs 62 and the rubber cushions 51a, Figure 7.

The central location of the hammer mechanism, in addition to its inherent steadiness, has the further advantage of eliminating the necessity for the heavy counter-balancing and anchoring required with over-hung hammer structures. Thus, since all the dead weight of the device is efficiently and evenly available for backing up the hammer blows, the invention provides a machine of high impact capacity with comparatively small size and weight. These latter qualities, together with the easy one-man maneuverability provided by the steering, propelling and braking means described, render the device especially applicable to work in crowded situations wherein larger machines could be operated only with great difficulty if at all. For example, the machine can readily be run down a sidewalk to cut openings for the installation of sub-structures.

Another example of work to which the device is especially adapted is the quick cutting of small openings in paved streets. Circular openings of approximately four foot diameter are a common requirement, and in preferred form

the present device may be properly proportioned to cut such openings with ease and rapidity by the method illustrated diagrammatically in Figure 9.

To carry out the method, the machine is run into position with the tire 23 of the rear wheel 20 resting at the center of the desired cutting path, and the wheel 20 is locked by means of the brake-shoe 31. As previously described. The front wheel 11 is swung to tangential position and the rear wheel 19 is revolved by the air-motor 27. This causes the entire machine to pivot about the locked rear wheel 20 as a center, and operation of the hammer 16 at the same time causes a circular cut to be made on the path 98 as desired, the radius of the path being the distance 99 between the vertical axis of the hammer mechanism and the center of the wheel 20. Since, as noted, circular cuts of about four feet diameter are a very common requirement, the machine may advantageously be proportioned to cut such holes by the locked wheel method described, but it will be obvious that the same machine may readily be used to cut larger or smaller openings of circular or any other desired shape simply by steering it in the proper path. The extreme mobility of the entire machine eliminates any necessity for any traversing or shifting means between the frame and the hammer mechanism, such as are required in prior devices with overhung hammers and the like.

Figure 8 illustrates an alternative form of elevating and cushioning mechanism for the air cylinder and hammer assembly.

Referring to Figure 8, each cross-head or trunnion member 100 is attached to the upper end of the piston rod 101 of a hydraulic cylinder 102, individual cylinders and rods being provided for the two cross-heads. A small hydraulic pump 103 is adapted to receive hydraulic fluid from a tank 104 and force the fluid into the cylinders 102 below pistons 105. The upper ends of the cylinders 101 are connected via tubes 106 with a small valve 107 adapted to supply compressed air or release the air above the pistons 105.

Elevation and lowering of the hammer and pneumatic cylinder assembly is accomplished by pumping hydraulic fluid into or releasing the fluid from the lower end of the cylinder 102. When the hammer is to be operated, compressed air is admitted above the pistons 102 to form cushions against upward motion. Similarly the hydraulic fluid supplies a degree of resilience below the pistons 102. Thus the entire hammer operating assembly is supported between hydraulic and pneumatic cushions which supplement the cushioning effect of the tires 18, 22 and 23.

While the invention has been described in preferred form it is not limited to the exact structures illustrated, as various changes and modifications may be made without departing from the scope of the appended claims.

What is claimed is:

1. In a device of the character described, in combination, a frame, vertical guides attached to said frame, a pair of cross-head members slidably disposed in said guides, a pneumatic cylinder having an upper and a lower head, lateral cylindrical extensions on said lower head trunnioned in said cross-head members, resilient

means to normally hold the axis of said cylinder parallel to said guides, a piston in said cylinder, a piston rod secured to said piston and slidably extending through said lower head, a hammer secured to the lower end of said piston rod, and adjustable means to support said cross-heads substantially at predetermined heights in said guides.

5 2. A device as claimed in claim 1 including an auxiliary vertical guiding member, and wherein said resilient means comprises a leaf spring centrally secured to one of said cross-head members, the terminal face portions of said spring engaging said auxiliary guide member.

10 3. A device as claimed in claim 1 wherein said supporting and locking means includes upper guide members attached to the said first-mentioned guides, vertical rods slidably mounted in said upper guide members and having their lower ends attached to said cross-head members, said rods having spaced parallel notches therein, and manually withdrawable latches attached to said upper guide members and normally engaging parallel notches in said rods.

15 4. A device as claimed in claim 1 wherein said supporting means includes second guide members attached in vertically cushioned relationship to said first mentioned guides, vertical rods slidably mounted in said second guide members, said rods having spaced parallel horizontal notches therein, latches pivoted to said second guide members and normally engaging parallel notches in said rods, and means operatively connected to said latches and including a single manually operable lever to simultaneously disengage said latches from said notches.

20 5. A device as claimed in claim 1 wherein said supporting means includes hydraulic cylinders below said cross-head members, said hydraulic cylinders having pistons therein and vertical rods attached to said cross-head members, and pumping means to force hydraulic fluid into said hydraulic cylinders below said hydraulic piston whereby said cross-heads and said pneumatic cylinder may be elevated and vertically supported in said guide members.

25 6. A device as claimed in claim 1 wherein said supporting means includes hydraulic cylinders below said cross-head members, said hydraulic cylinders having pistons therein and vertical rods attached to said cross-head members, pumping means to force hydraulic fluid into said hydraulic cylinders below said hydraulic pistons, and means including a control valve and conduits to admit compressed air to said hydraulic cylinders above said hydraulic pistons.

WALTER V. CORNETT.
